GOLF CLUB CARRIER

Will J. Worley, 1204 E. Delaware, Urbana, Ill.

Filed May 5, 1958, Ser. No. 50,736

Term of patent 14 years

(Cl. D34—5)

Fig. 1 is a perspective view of a golf club carrier showing my new design, the clubs shown in broken lines being for illustrative purposes only;

Fig. 2 is a side elevational view thereof;

Fig. 3 is a front elevational view, and

Fig. 4 is a top plan view with the handle grip portion of the carrier omitted for convenience of illustration.

I claim:

The ornamental design for a golf club carrier, substantially as shown and described.
